ATTORNEY.

UNITED STATES PATENT OFFICE.

EZRA F. BISHOP, OF OAKLAND, CALIFORNIA, ASSIGNOR OF ONE-HALF TO ROY W. DIMOCK, OF OAKLAND, CALIFORNIA.

VENDING SHOW CASE.

Application filed June 23, 1926. Serial No. 118,003.

My invention relates to a show case of the type arranged to have all merchandise displayed therein completely under cover so that surreptitious removal or undue exposure of the merchandise may be prevented, but which may be manipulated by the vendor to give a customer full access to the contents whereby the latter may choose and withdraw from the case the particular article desired without assistance from the vendor.

An object of the invention is to provide a show case of the character described having a plurality of independently-protected merchandise-display compartments, access to each one of which—thus to all the merchandise displayed in the case—may be given to the customer by a single operation on the part of the vendor.

Another object of the invention is to provide a show case of the character described, in which the merchandise is elevated or moved toward the customer at the same time as access to the same is given him.

A further object of the invention is to provide a show case with the foregoing advantages, which is dust proof, simple in construction, and very easy to operate.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figures 1 and 2 are vertical sectional views of the show case of my invention, respectively showing the same in closed and open positions.

Figure 3 is a rear elevation of the case, the scale of the figure being somewhat reduced.

Figures 4 and 5 are views similar to Figures 1 and 2, but showing a modified form of the case.

As illustrated in the preferred embodiment of my invention the case comprises a body 6 having front and rear walls 7 and 8, sides 9, and a bottom 10, a door 11 being provided for closing an opening 12 which is formed in the rear wall 8 and through which access may be had to the interior of the case. Mounted in the body for movement relative thereto is a unit 13 which is arranged to carry the merchandise for the display and vending of which the case is adapted for use. The unit is provided with side walls 14 and a front wall 15 which are arranged to slidably engage the corresponding walls of the body, proper bearing surfaces being preferably provided between the opposing walls. Formed at the upper portion of the unit are a set of horizontally-extending merchandise receiving compartments 17 arranged in steps progressing upwardly and rearwardly. As here shown each compartment comprises a bottom shelf 18, a back plate 18', and a transparent top plate 19, access to the merchandise in the compartments being afforded through an opening 21 at the front thereof.

The openings 21 are arranged to be fully covered by transparent glass plates 22 which are vertically disposed and are fixed to the body 6 of the case. It will thus be noted that the merchandise 23 in the compartments are completely protected when the openings 21 are closed, but that by reason of the provision of glass front and top plates, such merchandise is fully visible, and the display thereof, if anything, rendered more effective.

Means are provided exclusively under the control of the vendor, for simultaneously uncovering each of the openings 21 and at the same time moving the compartments toward the customer so that merchandise is more conveniently and effectively served to him. As previously noted the unit 13 is mounted for movement relative to the body and as illustrated in Figures 1 to 3 such unit is arranged to slide vertically in the body. When, as illustrated in Figure 1, the unit is in a lowered position, the openings 21 will be completely covered by the fixed plates 22, and top plates 19 which it will be noted project forwardly beyond the plates 22, will rest thereon and thus seal the com-

partment. However, when the unit is elevated as illustrated in Figure 2, the openings in each of the compartments will have moved sufficiently clear of the plates 22, to afford the customer ready access to the contents, and the merchandise will have been moved directly up to him.

Movement of the unit is here shown arranged to be effected by means of a single crank 24 which is fixed for rotation with a drum 26 mounted on a cross piece 27 of the body. Wound on the drum and attached at its ends to lugs 28 and 29 fixed to the unit, is a cable 31 by means of which as will be readily understood the rotative movement of the crank is transferred to rectilinear movement of the unit. Counterbalancing of the unit to render the operation thereof with a minimum effort on the part of the vendor, is preferably effected by means of a weight 32 which is carried by cables 33 passing over sheaves 34 suitably secured to the body, the free ends of the cables being attached to lugs 36 fixed to sides 9 of the unit. It will now be evident that a most effectively operating, but simple structure is provided.

In Figures 4 and 5, I have shown a modified form of the invention. In this embodiment the merchandise-supporting unit 40 is arranged to slide horizontally in the body 41, and conversely of the arrangement existing in Figures 1 to 3, the glass top plates 42 of the newer embodiment are fixed to the body whereas the front plates 43 are carried by the unit for movement with the compartments. Normally, as shown in Figure 4, the unit is in a retracted position and the openings 44 to the compartments are closed by the top plates 42, however by merely sliding the unit forwardly toward the customer the openings 44 will be uncovered and the customer will be given full access to all of the compartments. After the customer has been served, the vendor may draw the unit back into the body and the merchandise in the compartment will again be covered and protected.

I claim:

1. In a vending show case, a body, a merchandise supporting unit slidable vertically in said body and comprising horizontally extending merchandise holding compartments arranged in upwardly and rearwardly progressing steps, and having an opening across the front thereof through which access may be had to the compartment from the exterior of the case, vertically disposed transparent plates fixed to said body and so positioned relative to said compartments whereby they may seal said openings in one position of the unit or be to one side of said openings in another position of said unit and thereby permit access to the merchandise.

2. In a vending show case, a body, a merchandise supporting unit mounted to slide

vertically therein and comprising merchandise holding horizontally-extending compartments arranged in upwardly and rearwardly progressing steps and each being open at the front thereof, and independent vertically extending transparent plates fixed to said body and so positioned relative to said compartments that the openings thereof will be covered thereby when the unit is in one position or be uncovered thereby when the unit is in another position, and transparent top plates for said compartments movable with said unit and arranged to substantially set upon said front plates and thereby seal the compartments in one of the positions of the unit.

3. In a vending show case, a plurality of vertically-disposed relatively-fixed transparent plates arranged one above the other in different vertical planes, merchandise holding compartments each having an opening therein for giving access thereto from the exterior of the case and arranged to be closed by said plates, and means for movement of said compartments simultaneously so as to remove said openings from said closure plates and thereby permit access to all of said compartments at the same time.

4. A vending show-case in accordance with claim 3 characterized by said compartments being arranged to lie in a higher plane when said openings are exposed than when said openings are covered by the plates.

5. In a vending show case, a body, a member providing a merchandise holding compartment mounted for movement relative to said body, said compartment having an opening for permitting access thereto from the exterior of the case, transparent closure members fixedly positioned with respect to said body whereby said opening will be engaged thereby or removed therefrom in different positions of said compartment, and means for counterbalancing said compartment in its different positions.

6. In a vending show case, a body, a merchandise supporting unit mounted therein for reciprocative movement relative thereto and comprising a plurality of horizontal and fixedly related shelves arranged in upwardly and rearwardly progressing steps, a pair of transparent plates associated with each shelf and arranged to define a closure for the merchandise thereon, one of the plates of each pair being fixed to said unit and extending perpendicular to the plane of movement thereof, the other of said plates being fixed to said body and extending coplanar with said movement and so positioned relative to said shelving that in one position of said unit the second mentioned plates will cooperate with the first to shield the merchandise on the shelves, whereas in another position of said unit the shelving will be sufficiently out of the range of said second

- plates to afford access to said merchandise from the exterior of the case, means for counterbalancing said merchandise supporting unit in its different positions, and hand 5 operated means for moving said unit from one position to another.
7. In a vending show case, a body, a merchandise supporting unit mounted thereon for reciprocal movement relative thereto 10 and comprising a plurality of merchandise supporting shelves, a transparent plate associated with each shelf and so related to its shelf as to provide a closure for the merchandise on the shelf when said unit is in one position with respect to the body and 15 to permit access to said merchandise when the unit is in another position thereof, and means for counterbalancing said unit in its different positions.
8. In a vending show case, a plurality of 20 fixed transparent plates, merchandise holding compartments each having an opening therein for giving access thereto from the exterior of the case and arranged to be normally closed by said plates, and means for effecting like movements of said compartments simultaneously so as to remove said openings from said closure plates and thereby permit access to all of said compartments at the same time. 30

In testimony whereof, I have hereunto set my hand at California this 10th day of June, 1926.

EZRA F. BISHOP.
